UNITED STATES PATENT OFFICE

ANDERS JOSEF JONSSON, OF LINKÖPING, SWEDEN

CAPPING MACHINE

Application filed April 17, 1928, Serial No. 270,777, and in Norway February 22, 1928.

This invention refers to capping machines with several so called capping heads where the cap stamped out from a metal strip is inserted pneumatically and where it is then fastened automatically on the bottle. The invention has for its object to facilitate in machines of this kind the adjusting for bottles of different height.

In holder machines, that is to say, machines without pneumatic insertion of the caps in the capping heads, these are mounted in a part of the frame which may be raised and lowered for adjusting the heads to the height of the bottles on the machine table which is stationary.

The said adjusting device cannot be used in machines with pneumatic insertion, because the opening of each capping head through which the cap is inserted therein must be of an invariable width determined exactly in relation to the horizontal surface on which the cap slides on to the opening. The fact that the machine may be adjusted to bottles of different height or, in other words, to the distance between the machine table and the capping heads is, evidently, very vital, as the machine otherwise cannot be used for more than one size of bottles. To make the machine table so as to be raised and lowered, which is close at hand, has met with difficulties by reason of the table being connected to a great portion of the mechanism of the machine. These difficulties are overcome by this invention which is described below and shown diagrammatically in the accompanying drawings, where—

Figure 1 is a side-view,

Figure 2 is a horizontal section on the line II—II of Figure 1, and

Figure 3 is a side-view on a greater scale, partly a vertical section.

The capping heads 1 are as usual adapted for rotating on a column 2 which is fixed to the floor by a base-plate 3 and screws with nuts 4, 5. Each head 1 has an opening 6 (Figure 1) for the insertion of the cap in the head, which is effected when the head is on the back-side, considered from the spectator, and the respective cap is blown into the opening on a path 7 (Figure 2). Synchronously with the heads 1 a nave 8 rotates in which supports 9 are disposed pushing up the bottles 10, each into one head, when the cap is to be fastened on the bottle. The said nave 8 is surrounded by a casing 11 located round the column 2 so as to be raised and lowered, the machine table 40 resting on the said casing. The bottles are moved automatically out to the machine by an endless conveyor belt 12 running between guides 13 resting on uprights 14. When the bottles, the one after the other, reach the machine they are seized by a turnable catcher 15 which places them each on one support (Figures 1 and 3). An arched railway 16 guides the bottles in their movement with the catcher 15. During the rotation round the column 2 the bottles are maintained in their position each on its support by a ring 17 which synchronously partakes in the rotation of the heads and has a recess 18 for each bottle. The heads 1, the nave 8 and the ring 17 are mounted on a tube 20 around the column, the said tube being supported by ball-bearings 21 resting on the base 22 of the column. The said tube is besides mounted around a bearing sleeve 42, and it is rotatated by a mitre wheel gearing 23, the shaft 24 being driven by mechanical power. The heads 1 are fixed to the tube 20, but the nave 8 and the ring 17 can be pushed up and down on the same. They are, however, caused to rotate with the tube by wedges 25. The nave 8 is supported by an annular flange 26 in the casing 11, the said annular flange serving also as bearing for the nave. The upwards and downwards motion of the supports 9 is effected by a cam 27 fixed to a shoulder 41 on the inside of the casing. When during the rotation of the nave 8 a support reaches the cam 27 a roller 29 on a pin 28 of the support rolls up on the cam, the support being then raised. When the roller has passed the highest portion of the cam the support sinks down again. At the same time as a cap is blown into a head 1 the bottle is moved under the said head by the support 9 and the cam 27 respectively. When the support has reached its highest position the neck of the bottle must be in a determined height position in the head 1 for allowing the cap to

be fastened. The said position is determined by the raising or lowering of the supports, not separately but commonly and together with the whole casing 11 and members located therein, in order that the adjustment may be made quickly and safely.

The adjustment is effected by a screw device. The screw 30 is mounted in a lateral projection 31 of a ring 32 around the column 2, the

10 said ring being connected with the casing 11, and the screw 30 can be screwed up and down in the base-plate 3, when the casing 11, the cam 27, the supports 9, the nave 8 and the table 40 follow. The screw 30 is rotated by 15 a mitre wheel gearing 34 and a hand-wheel 35. For the shaft 24 there is a groove 36 in the casing, which facilitates the raising of the casing independent of the shaft. When a support with its bottle has passed over the 20 cam 27 and the bottle has got to the vicinity of the conveyor belt 12 it slides over onto the same along the arched railing 37 and is then moved further on the conveyor belt for labeling, packing or the like.

25 In order that the bottles may be forwarded to the machine and removed from it in a continuous manner independent of the height position of the supports 9 et cetera, the lateral guides 13 for the conveyor belt have been 30 provided with joints 38, for example two on each side, so that the conveyor within the joints takes part in the raising and lowering of the table while the remaining part of the conveyor remains in the same vertical position, supported as it is by the uprights 14. Figure 3 shows the belt by dot and dash lines 35 in its lowered position.

The invention, such as it is stated in the following claims is, evidently, not limited to 40 the shown embodiment.

Having now described my invention, what I claim as new and desire to secure by Letters Patent is:

1. In a machine for applying caps to 45 bottles, the combination with capping heads rotating about a central column, of a machine table having supports carrying the bottles and elevating them into said heads, a nave rotating with the latter about the column and 50 carrying the supports for the bottles in upright positions, a frame supporting the nave and machine table, a conveyor for the bottles traversing a portion of the table, and an adjustment device for changing the elevation 55 of the frame and with it the table, conveyor, nave and supports therefor.

2. In a machine for applying caps to bottles, the combination with capping heads rotating about a central column, of a machine table 60 having upright supports carrying the bottles and elevating them into said heads, a nave rotating with the latter about the column and carrying the supports for the bottles, a conveyor for the bottles traversing a portion of 65 the table, a frame supporting the nave and

having a cam in the path of the supports to elevate the same, and means for adjusting the elevation of the frame, nave, supports, table and conveyor, comprising a screw operating in the frame and a handle wheel operatively connected to the screw to revolve same.

In witness whereof, I have hereunto signed my name.

ANDERS JOSEF JONSSON.
